UNITED STATES PATENT OFFICE

ALBERT W. SMITH AND JAMES M. NELSON, OF YOUNGSTOWN, OHIO

METHOD OF AND APPARATUS FOR CASTING METAL

Application filed September 17, 1928. Serial No. 306,305.

A principal object of the present invention is to provide a method of casting metal, more particularly steel ingots, as well as an apparatus adapted for the performance thereof, by means of which ingots of greater uniformity and improved quality can be produced than by the methods of casting and apparatus which have hitherto been employed.

Further objects and advantages of, and novel features of operation, design, construction and arrangement of parts and instrumentalities embraced by the invention are herein-after more particularly pointed out or will be apparent from the following description 15 of one manner of performing our improved method by means of the apparatus illustrated in the accompanying drawings.

As will hereinafter more fully appear, our invention contemplates the simultaneous filling 20 of a plurality of ingot molds by introducing the molten metal at the bottoms thereof, that is, by "bottom pouring" as it is termed in the art, so as to simultaneously produce a corresponding number of ingots and in such 25 manner that the metal flowing to each mold from its point of introduction to the apparatus is constrained to traverse exactly the same distance from said point to each of the several molds; in consequence, the metal reaches all of the molds in exactly the same 30 condition as to pressure, temperature, fluidity and the like with the result, among other things, that each of the several ingots is formed under exactly the same conditions as 35 all of the other ingots, with resulting uniformity therein. Additionally, after the initial pouring has been completed and the "refill" operation undertaken as hereinafter more 40 fully explained, and the primary function of which is to eliminate pipes from the ingots as far as possible, the uniformity of pressure exerted by the refill metal in the several molds results in the introduction of exactly the same 45 amount of refill metal into each mold and under the same conditions as in the case of all of the other molds, so that unequal refilling of the molds is avoided as well as any bursting through of the solidified "skin" or crust 50 at the upper ends of those ingots which are

more closely adjacent the pouring fountain through which the metal is introduced.

To enable those skilled in the art to comprehend and practice the invention, we shall now describe one manner of performing our improved method by means of an apparatus such as is illustrated in the said drawings and in which Fig. 1 is a top plan view of the apparatus as assembled preparatory to the casting operation; Fig. 2 a vertical section thereof on line 2—2 in Fig. 1, and Fig. 3 a fragmentary vertical section thereof on line 3—3 in Fig. 1, both of said sections being taken in the directions indicated by the arrows on the section lines and the same symbols being used to designate similar parts in the several figures.

The particular apparatus which we have chosen to illustrate is suitable for the simultaneous production of sixteen ingots but, of course, it will be understood that the apparatus may be arranged for the simultaneous production of a greater or lesser number of ingots if desired without departing from the principles of the invention; however, in practice good results have been obtained with an apparatus designed as shown.

The apparatus comprises a base or stool 2 which may take the form of a rectangular relatively thick plate of metal suitably 30 grooved or channeled in its upper surface for the reception of bricks of refractory material which form, among other things, the passages through which the metal passes to the several molds 3 which, as shown, may take the form of hollow cylinders open at their upper and lower ends, which latter simply rest upon the upper surface of the stool.

Disposed at the center of the stool is the pouring fountain, generally designated as 4, into which the metal is poured or teemed during the casting operation; this fountain may comprise a hollow cylindrical metal casing 5 having a tubular brick lining 6 and a funnel 7 at its upper end also suitably brick lined as at 7'. At its lower end the casing 5 may be enlarged to form a base 8 which rests on the surface of the stool and securely supports the fountain in upright position; the base 95 may be provided with a tubular brick lining 100

8' forming a substantial extension of the lining 6 and seating upon a single cup-shaped brick 9, or a plurality of brick segments together forming a cup-shaped unit, disposed in a recess at the center of the stool and embodying a central cavity 10 forming a sump into which the metal can flow from the fountain. From the recess in which the brick lining is disposed radiate the main channels 12 in which are disposed bricks forming the main metal passages; these main channels are of sufficient depth to receive two courses of bricks one above the other and are preferably disposed at right angles to each other so that 15 the four channels in effect form the arms of a cross. In each of these main channels 12 are two courses of bricks disposed one above the other, the lower courses of bricks 14 being longitudinally pierced to form the lower 20 metal passages 15 and being conveniently of substantially rectangular cross sections so as to fit more or less snugly in the channels 12. The innermost brick 14' in each of these channels, that is, the brick most nearly adjacent 25 to the central fountain 4, is, however, of somewhat different shape than the other bricks in that its innermost end is closed and its central opening or passage extended through its upper wall to register with a corresponding opening in the lower wall of the 30 superjacent brick 16 in the upper course, the metal passage through this brick 16 being closed at its outer end and communicating at its inner end with a port 17 in the wall of the cup-shaped brick 9 forming the sump 10. The passage through the two complementary 35 bricks 14' and 16 thus forms a vertically disposed slag trap 18 between the sump 10 and the lower metal passage 15 through which the metal must pass after it leaves the sump 40 while the outermost brick 14'' in each of the lower courses also differs from the central bricks therein in that it is closed at its outer end save for a small air vent 19 extending therethrough and the purpose of which will 45 hereinafter appear.

Disposed above the lower course of bricks in each of the main channels is a second course of substantially similar bricks with 50 their upper surfaces lying substantially flush with the surface of the stool. As in the case of the bricks in the lower courses, the central bricks 22 of those forming the upper courses are longitudinally pierced from end to end to 55 form the upper metal passages 23 while the inner ends of the innermost bricks 22' are closed and provided with air vents 24 and the outer ends of the outermost bricks 22'' similarly closed and provided with air vents 25.

60 If desired, a small clearance may be left between the extremity of each innermost brick 22' and the end of the adjacent brick 16 so as to facilitate escape of air through the vents 24. Ports 26 are provided in the upper walls 65 of the end bricks 22' and 22'' through which

the metal can pass from the upper passages 23 to the superjacent molds 3 during the casting operation.

Midway between the ports the stool is provided with auxiliary upper channels 27 respectively disposed at right angles to the adjacent main channels and extending in opposite directions therefrom but only cut into the surface of the stool for one-half the depth of the main channels so as to contain 70 but one course of metal-passage-forming bricks 28 which are disposed therein in a way generally similar to the upper bricks in the main channels and in the same horizontal plane; similarly also the outermost bricks 28' in the auxiliary channels have their ends closed and provided with air vents 29 and are also respectively provided with ports 30 in their upper walls through which the metal can pass from the passages 31 to the superjacent molds 3 respectively adjacent thereto and thus generally corresponding to the ports 26 heretofore described. It will thus be apparent that the upper and lower courses of 80 bricks in the main channels and the single course of bricks in the upper channels for each group of four molds converge radially upon a common center about which the ports 26 and 30 are equidistantly disposed.

At this central point of convergence of the bricks in the respective groups of channels the brick work is so formed as to provide a central riser, generally designated as 34, disposed in a recess 35 suitably located in the stool at the intersection of the main and auxiliary channels; through which riser the metal can ascend from the passages in the lower courses of bricks to pass into the passages in the upper courses disposed in the channels 12 and 27 and thence through ports 26 and 30 to the superjacent molds. Each of these risers is desirably open at the top and operatively closed by means of a cap 35' which may be hollowed out as shown in Figs. 2 and 3 to form an auxiliary slag trap for a purpose hereinafter more fully explained, but as the upward pressure on these caps during the pouring operation is considerable it is requisite to hold them in place by some suitable means, as, for example, by weights 100 36 which are rested on the caps. To form a packing for the joints between the margins of the caps and the subjacent bricks a retaining ring 37 of greater diameter than the cap may be disposed about each of the latter and the space between the ring and the cap filled with loam 38, clay or the like, but any other means of holding the caps in position or packing the joints between them and the subjacent brick work may be utilized 105 if preferred.

As shown, the channels are somewhat longer than the total of the metal-passage-forming bricks disposed therein so as to leave a small space beyond the courses of 110 115 120 125 130

bricks at the outer end of each channel which may be more or less loosely filled in with old brick work or like material 40 after the bricks are in place so as to hold the latter in longitudinal engagement. It will be noted that in the drawings we have shown a very small clearance 41 between this filling-in material and the ends of the adjacent bricks so as to allow for the escape of air 10 from the metal passages through the air vents in these bricks; in practice, however, as the filling-in brick work 40 is not solid but is formed from irregularly shaped pieces there is no necessity for providing this clearance as the air from the metal passages will readily escape through the interstices between the pieces of filling-in material.

It will thus be apparent that the ports 26 and 30 through which the metal passes 20 from the metal passages to the mold are symmetrically arranged in groups about the several risers 34; consequently that when the molds 3 are respectively disposed adjacent these ports substantially coaxially therewith 25 they will be similarly grouped as shown in Fig. 1 and further that, in turn, the risers 34 are all equidistantly spaced from the central sump 10 with which the pouring fountain communicates and are connected therewith 30 by the inner portions of the lower metal passages 15 and slag traps 18 communicating with the ports 17 extending into the sump. Preferably, as shown, the lower course of bricks in the main channels is laid 35 on a thin bed of loam or clay 42.

When casting ingots in an apparatus substantially of the character of that to which reference has been made, the fluid metal is teemed into the funnel at the top of the 40 pouring fountain and thence passes from the sump 10 through the ports 17 to the slag traps 18 and thence to the lower metal passages 15 through which it flows until the passages are filled. In its passage through the 45 traps 18 the slag and other lighter impurities are skimmed off of the metal and remain in the traps so that the metal entering the metal passages 15 is relatively free from impurities. However, any impurities such 50 as brick scourings or the like which may pass through the traps 18 are almost entirely confined to the leading portions of the streams of metal with the result that they are carried into the extremities of the metal passages 15 55 beyond the risers 34 with the first rush of metal and thereafter remain therein and do not pass upwardly through the risers to the upper metal passages; moreover, as the air is fully vented from the passages 15 by the 60 vents 19 there is no compression thereof in the extremities or dead ends of these passages and thus no tendency for the metal to be driven or splashed back and thrown upwardly into the molds or upper passages before the regular and even flow of metal there-

to is established with resultant production of "scabby" ingots. Hitherto this result has frequently occurred where the metal was allowed to flow into dead end but unvented passages beneath the molds but as in accordance with our invention the dead ends of all of the metal passages are fully vented this back splashing of the metal and inimical effects resulting therefrom, due principally to the adherence of the splashed metal to the sides of the molds, are substantially eliminated.

After the lower metal passages 15 are completely filled, the metal passes upwardly through the several risers 34 into the upper metal passages and completely fills them before passing therefrom to the superjacent molds through the ports 26 and 30, and since, as in the case of the lower metal passages, the dead ends of the upper passages are filled in advance of the entrance of the metal to the molds and as these dead ends are likewise thoroughly air-vented, any back splashing of the metal is likewise substantially eliminated just as in the case of the lower passages. Furthermore, any lighter impurities 90 which may remain in the metal after its passage through the risers 34 are collected in the hollowed out caps 35' above the risers which act as additional slag traps so that by the time the metal emerges from the ports 26 and 30 substantially all such impurities are eliminated therefrom.

The flow of metal through the molds having been thus established, the teeming thereof into the fountain 4 is continued until the 100 molds are filled to the desired height after which the teeming may be either temporarily or permanently discontinued and the ingots allowed to cool; if desired and in accordance with the usual practice the cooling of the 105 ingots may be hastened by playing a stream of water on their exposed extremities. During this cooling the metal of each ingot shrinks appreciably and a pipe or depression is formed in its upper end upon which, as 110 well, a relatively hard skin or crust is formed, and for the purpose of eliminating these pipes as far as possible it is customary to fill the fountain with additional metal known as "refill metal" after the ingots have been cooled for a predetermined period. As the 115 ingots continue to shrink internally this additional metal in the fountain gradually feeds to the ingots and serves to minimize the formation of the pipes and at a suitable 120 time after the completion of the refilling operation, or after the initial pouring of the ingots if the refilling operation is omitted, the molds are removed from the solidified ingots and the latter allowed to cool and thus reach a condition suitable for subsequent treatment.

In the casting of ingots as heretofore practiced the distance traversed by the metal in its passage from the pouring fountain to the 130

several molds varies in accordance with the distance of the latter from the fountain in consequence of which those molds more nearly adjacent the fountain receive the metal at greater pressure and frequently in a state of greater fluidity than those molds more remote therefrom. This results, among other things, in considerable swirling and other disturbances of the metal in those molds nearest the fountain with consequent production of scabby ingots and, further, in these molds generally receiving more metal than the others with resultant production of longer ingots. Moreover, during the refill operation, if employed, the pressure of the refill metal in those molds most nearly adjacent the fountain is materially greater than in those more remote therefrom due principally to the chilling of the metal in the longer metal passageways to the former during the initial cooling of the ingots with the result that the refill metal frequently breaks through the skin or crust of the ingots subjected to the greatest pressure and exudes therefrom while on the other hand, insufficient metal is supplied to the others to eliminate or minimize the formation of pipes therein.

It will be noted, however, that in accordance with our invention the fluid metal is constrained to travel exactly the same distance from the fountain to each of the several molds irrespective of the actual distance of the molds from the fountain. In consequence, as the metal is thus fed to all of the molds under exactly the same conditions as to fluidity, temperature and pressure, all of the several ingots are formed under like conditions. And here resides one of the important features of our invention for it enables, among other things, the simultaneous production of a plurality of ingots which are substantially uniform both as regards density and size, while, furthermore, during the refilling operation, if employed, each ingot receives exactly the same amount of metal under the same pressure as every other ingot.

A further advantage of our invention resides in the elimination to a very large extent of surface cracks in the ingots which under present methods of casting very frequently result from the swirling motion of the metal in those molds to which the metal can pass most easily from the pouring fountain and which are usually those molds most nearly adjacent thereto. These surface cracks are also sometimes due to the refill metal breaking the thin surface of some of the ingots when the pressure of the said metal is greater in one mold than in another, a condition which for the reasons pointed out cannot occur when the pressure in each of the molds is uniform with that in all of the others.

Moreover, since in accordance with our invention each of the molds is simultaneously filled to the same depth or height as all of the

other molds, all of the ingots are of uniform length with resulting diminution of the amount of metal which must be cut off and scrapped; this is a very important advantage of our invention since in the production of ingots the lengths thereof are calculated on the amount of finished produce desired with the minimum amount of scrap. Thus, when some of the ingot molds, usually those more remote from the pouring fountain, fill more slowly than those adjacent thereto, it is necessary, in order to have the ingots cast in the former of the desired length, to make those cast in the latter of excessive length and to then later cut them off and discard the excess, thus increasing the cost of production because of the undue amount of scrap which must be removed.

We are also enabled in accordance with our invention to effect a much better control of the filling of the molds than has heretofore been possible, for, due to the uniform conditions in all of the molds, any modification of the rate of flow to the pouring fountain or the like is equally effective upon all of the molds simultaneously; in addition, the metal flows smoothly and freely to all of the molds at a uniform rate and without undue pulsating effects in any of them, while due to the interposition of the slag traps in the metal passageways through which the metal must pass prior to its entrance to the molds, we are able to free the metal very largely from impurities and thus produce cleaner and more satisfactory ingots.

It will be noted that in accordance with the preferred practice of our invention the molds are very closely grouped together upon the stool and that the metal passageways are comparatively short with consequent avoidance of any undue chilling of the metal before reaching the molds; additionally, in consequence of the massed disposition of the molds better cooling effects are obtainable both before and after removal of the molds from the ingots as the cooling of the latter is materially retarded with resultant diminution of surface strains in the ingots to a minimum.

It will be apparent that ingot molds of different sizes may be utilized as desired without disturbing the other parts of the apparatus and thus, while it is generally preferable that all of the molds employed in one cast should be of the same size, it is immaterial whether they be relatively large or small so long as they are capable of being respectively disposed upon the stool in substantial axial alignment with the several ports 26 and 30. It is therefore possible, without sacrificing any of the advantages of the invention, to employ with the same stool and arrangement of brick work any of the usual sizes of ingot molds, while because of the compact arrangement of the molds upon the stool, the apparatus when designed to pro-

duce a given tonnage in a single cast can be made of smaller size than those forms of apparatus heretofore employed, with consequent reduction in the size of the building and pouring pit in which it is housed and in the crane trackage and other auxiliary mechanism requisite for the handling of the fluid metal and the like. Moreover, as with a given stool the same brick work and sizes 10 of bricks may be utilized irrespective of the dimensions of the molds which are to be employed, we are able by our invention to effect material economy in plant operation by eliminating the necessity for keeping on hand 15 a plurality of bricks of different sizes, thus cutting down the space requisite for the storage of bricks as well as the capital invested in the amount of bricks which must be kept on hand, the reduction in brick inventory 20 which we are thus able to effect amounting in some cases to as much as 60%.

While we have herein described one form of apparatus adapted for the performance of our invention with considerable particularity, we do not thereby desire or intend to specifically limit ourselves thereto nor to confine the use of our improved method solely to the casting of steel ingots as the same may be employed for the casting of other metals 25 if desired while various changes and modifications may be made in the details of construction and arrangement of the apparatus itself without departing from the spirit and scope of the invention as defined in the appended claims.

Having thus described our invention, we claim and desire to protect by Letters Patent of the United States:

1. The method of bottom casting a plurality of ingots simultaneously which comprises the steps of teeming molten metal to a distributing point and then conducting said metal from said point in a plurality of different streams of equal length to a plurality of ingot molds arranged at different distances about said point.

2. The method of simultaneously bottom casting a plurality of ingots which comprises the steps of teeming the molten metal in a single stream to a distributing point and then distributing the metal from said point in a plurality of different streams to a plurality of ingot molds disposed at different distances 55 from said point by conducting the metal to each of said molds through paths of equal length.

3. In a method of bottom casting a plurality of ingots simultaneously, the steps of conducting the molten metal from a central distributing point through substantially equal distances to each of a plurality of molds disposed about said point at different distances therefrom to thereby cause the metal to reach 60 each of said molds under substantially the

same conditions as to pressure, fluidity and temperature.

4. In a method of simultaneously bottom casting a plurality of ingots, the step of effecting equal distribution of the molten metal from a central distributing point to a plurality of ingot molds disposed thereabout and at different distances therefrom by causing the metal to flow from said point substantially the same distance to each of said molds. 70

5. In a method for simultaneously bottom casting a plurality of ingots, the step of effecting equal distribution of the molten metal from a central distributing point to a plurality of ingot molds disposed thereabout and at different distances therefrom by causing the metal to flow to each of said molds from said distributing point through passages of equal length to thereby cause the metal to enter each of said molds under substantially the same conditions as to pressure, temperature and fluidity. 80

6. In an apparatus for casting metal a plurality of molds arranged at different distances about a central distributing point, means for supporting the molds, and means for conducting molten metal from said point to the bottom of each mold and adapted to cause the metal in its passage to each mold to traverse the same distance from said point. 90

7. In an apparatus for casting metal, a plurality of molds arranged at different distances about a central sump, a stool for supporting the molds, and means for conducting molten metal from said sump to the bottom of each mold comprising a plurality of main channels formed in the supporting means and extending outwardly from the sump, auxiliary channels intersecting the main channels and refractory material lining all of said channels and providing passages for the metal. 100

8. In an apparatus for bottom casting metal, a pouring fountain, means for supporting the fountain, a plurality of molds disposed on said supporting means about the fountain at different distances therefrom, and means for conducting molten metal from said fountain to the molds simultaneously and adapted to cause the metal passing into each mold to traverse the same distance from the fountain. 110

9. In an apparatus for bottom casting metal, a stool having a plurality of channels in its surface, a pouring fountain supported on the stool, a plurality of ingot molds disposed on the stool about the fountain at different distances therefrom, and means disposed in the channels of the stool operative to form passages for conducting molten metal from below the fountain to the several molds and so arranged as to cause the metal in its passage to each mold to traverse the same distance through said passages. 115

10. An apparatus for casting metal com- 120

- prising a channeled stool, a pouring fountain supported on the stool, a plurality of ingot molds disposed on the stool about the fountain at unequal distances therefrom and 5 means disposed in the channels of the stool forming conduits for conducting the metal from the fountain to the ingot molds and arranged to cause said metal in its passage to each mold to traverse the same predetermined 10 distance, and slag retaining means in said conduits operative to trap impurities from the metal during its passage therethrough.
11. An apparatus for casting metal comprising a stool having in its surface a plurality of channels symmetrically arranged with 15 respect to each other and converging to a central sump and a plurality of other channels respectively intersecting said first mentioned channels and of one-half the depth thereof, a pouring fountain disposed above said sump, a plurality of ingot molds disposed about said fountain at different distances therefrom, and refractory material disposed in said channels and forming superimposed 20 passages adapted to conduct molten metal from the sump through said first mentioned channels to certain of said molds and other passages operative to conduct metal through said second mentioned channels from the 25 first mentioned passages to others of said molds, the passages being so arranged as to cause the metal flowing to each of the molds to traverse the same distance from the sump.
12. An apparatus for bottom casting metal comprising a mold supporting stool having a 30 plurality of main channels radiating outwardly from a single point and an auxiliary channel intersecting each of the main channels, a pouring fountain disposed above said 35 point, a plurality of molds seated on the stool above the channels, refractory lining material disposed in the channels and provided with passages for conducting the molten metal from the fountain to the several molds 40 through paths of substantially the same length, and means adapted to conduct air from said passages in advance of the metal as it flows therewith.
13. An apparatus for bottom casting metal comprising a mold supporting stool and a 45 pouring fountain disposed substantially at the center thereof, the stool being provided with a plurality of main channels formed in its upper surface and extending from the 50 fountain and an auxiliary channel crossing each main channel adjacent its outer end, a plurality of molds disposed on said stool above said channels and symmetrically arranged in groups about the point of intersection of each main and auxiliary channel, refractory lining material disposed in all of said channels and provided with passages for conducting the molten metal from the fountain to the several molds through different 55 paths of substantially the same length, means 60 in each passage adjacent the base of the fountain adapted to remove and trap impurities from the metal, and means for venting the air from each passage in advance of the metal as it flows to the molds.
14. An apparatus for bottom casting metal comprising a mold supporting stool and a pouring fountain disposed substantially at the center of the stool, the stool being provided with a plurality of main channels formed in its upper surface and extending from the fountain and an auxiliary channel crossing each main channel adjacent its outer end and of substantially one-half the depth of the main channel, a plurality of molds disposed on said stool above said channels and symmetrically arranged in groups about the point of intersection of each main and auxiliary channel, refractory lining material disposed in each main channel and provided with superposed passages for conducting molten metal from the fountain to the molds disposed above said main channel, refractory lining material disposed in each of said auxiliary channels and provided with a passage for conducting molten metal from the first mentioned passages to the molds disposed above said auxiliary channels, and means for venting the air from each of said passages in advance of the molten metal as it flows therewith, all of said passages being so arranged as to conduct the metal through substantially the same linear distance from the fountain to each mold.
15. An apparatus for bottom casting metal comprising a mold supporting stool and a pouring fountain disposed substantially at the center thereof, the stool being provided with a plurality of main channels formed in its upper surface and extending from the fountain in different directions and an auxiliary channel crossing each main channel adjacent its outer end, a plurality of molds disposed on said stool above said channels and symmetrically arranged in groups about the point of intersection of each main and auxiliary channel, refractory lining material disposed in each of said main channels and provided with a lower metal passage extending from beneath the fountain substantially to the outer end of the channel and an upper metal passage substantially parallel to the lower metal passage and communicating with the superjacent molds, means forming a connection between the upper and lower passages, refractory lining material in each auxiliary channel provided with passages extending from said connecting means to the superjacent molds, means for venting the air from the ends of all of said passages in advance of the molten metal as it flows therewith from the fountain, and means disposed adjacent the fountain and forming a connection with each of the lower metal passages.

adapted to intersect and trap impurities from the metal as it flows into said lower passages.

16. In an apparatus for casting metal, a plurality of molds arranged at different distances about a central sump, a stool for supporting the molds, and means for conducting molten metal from the sump to the bottom of each mold comprising a plurality of inter-communicating passages arranged in the stool at different levels and connecting each mold with the sump.

75

17. In an apparatus for casting metal, a plurality of molds arranged at different distances about a central sump, a stool for supporting the molds, and means for conducting molten metal from the sump to the bottom of each mold comprising passages in the stool and extending in a plurality of planes and so arranged that the metal is caused to traverse substantially the same distance to each mold from the sump.

80

18. In an apparatus for bottom casting metal, a pouring fountain, means for supporting the fountain, a plurality of molds disposed on said supporting means about the fountain at different distances therefrom, and means for conducting molten metal from the fountain to the molds simultaneously comprising a plurality of passages extending in the supporting means at different levels and arranged to cause the metal passing into each mold to traverse the same distance from the fountain.

85

19. In a method for simultaneously bottom casting a plurality of ingots, the steps of effecting equal distribution of the molten metal from a central distributing point to a plurality of ingot molds disposed thereabout and at different distances therefrom by causing the metal to flow to each of said molds from said distributing points through passages of equal length extending in a plurality of different planes whereby the metal is caused to enter each of said molds under substantially the same conditions as to pressure, temperature and fluidity.
